UNITED STATES PATENT OFFICE.

ANTHONY VANDERVELD, OF GRAND RAPIDS, MICHIGAN.

ANTISPINNING DEVICE FOR CLOTH-MEASURING MACHINES.

Application filed November 25, 1922. Serial No. 603,882.

To all whom it may concern:

Be it known that I, ANTHONY VANDERVELD, a citizen of the United States of America, residing at Grand Rapids, in the county 5 of Kent and State of Michigan, have invented certain new and useful Improvements in Antispinning Devices for Cloth-Measuring Machines; and I do hereby declare the following to be a full, clear, and 10 exact description of the invention, such as will enable others skilled in the art to which it appertains to make and use the same.

This invention relates to an automatically operating means in conjunction with the 15 measuring roller of a cloth measuring machine for stopping rotative movement of the roller immediately when the cloth has passed by the roller, as in the measuring of end pieces or remnants of cloth or the like in the 20 machine. Without this means, it is possible to cause the roller to turn a considerable amount after the cloth has passed, thereby giving a larger amount on the indicating means operated by the measuring roller than 25 is the actual length of the cloth measured. The present invention is designed to stop the roller against such rotative movement through the agency of a brake applied to the roller automatically with the departure of 30 the end of the cloth from the roller, and it is a primary object and purpose of the present invention to provide this means in simple form and of such construction that its working is sure and positive at 35 all times for the accomplishment of the ends desired, no possible over measurement of the goods occurring. Many other minor objects and purposes subsidiary to this main purpose will later appear as understanding of 40 the invention is had from the following description of the invention illustrated as to its preferred embodiment in the accompanying drawings, in which,

Fig. 1 is a fragmentary vertical section 45 through the measuring roller and adjacent parts of a measuring machine equipped with the invention.

Fig. 2 is a fragmentary vertical section 50 through the machine at a plane back of the plane of the section shown in Fig. 1.

Figs. 3 and 4 transverse vertical sections 55 through the measuring roller and the control means therefor, showing said means in two different positions, in one of which the said means is inoperative and ineffective, and in the other operative and effective, the

section being substantially on the plane of line 3—3, of Fig. 1.

Fig. 5 is a fragmentary transverse vertical section through the machine substantially 60 on the plane of line 5—5 of Fig. 1, showing the position of the parts while cloth is being drawn through the machine.

Fig. 6 is a like view, showing the position 65 of the parts as the end of the cloth leaves the rollers.

Fig. 7 is a perspective view of the brake roller carrying cage, forming an element of the construction, and

Fig. 8 is a perspective view of the member 70 used to be controlled by the cloth passing through the machine for governing the position of the brake with respect to the measuring roller.

Like reference characters refer to like 75 parts in the several figures of the drawings.

As constructed, the machine includes a base 1 from which an integrally cast post 2 extends upwardly, the mechanisms of the measuring machine being located above said 80 base and covered by housings 3 and 4, the latter of which is located at the lower front portion of the machine and including a horizontal table separated from the adjacent lower edges of the upper housing 3 a short distance, thereby providing a slot 5 through 85 which the cloth 6 is drawn in operating the measuring mechanism of the machine.

The measuring mechanism includes a measuring roller 7 secured on a shaft 8, the 90 front end of the shaft being rotatably mounted in a roller bearing 9 located in a suitable housing 10 which is permanently secured to the rear side of a front plate which, together with other plates 11^a at the sides, and a rear 95 plate (not shown), constitutes a supporting frame for carrying the mechanism. The housing for the roller bearing has a cylindrical outer surface except at two diametrically opposite points where it is flattened, 100 as indicated at 10^a.

The cloth 6 is pressed against the roller 7 by a presser roller 12, rotatably mounted in a frame which has two arms 13 and 14 paralleling each other, the frame being 105 pivotally mounted on a shaft or rod 15 (Fig. 5). The arm 13 has an extension 13^a to lie over one end of a lever 16 (Fig. 2) pivotally mounted between its ends on a suitable stationary part of the machine. The opposite 110 end of the lever passes under a cam 17 fixed at the end of a shaft 18 which passes through

and is rotatably mounted in the post 2, at its outer end having an operating handle 19 (Fig. 5) fixed thereto for manual operation. The cam 17 at one side has a cam projection 17^a which, on rotation of the shaft and movement of the cam rides over and against the end of lever 16, depressing such end and elevating the opposite end with a consequent elevation of the extension 18^a and lowering of the presser roller 12, moving it away from the measuring roller and holding it away until the handle 19 is operated in the opposite direction. The construction so far described is old and has been previously invented and built by me.

An irregularly shaped member 20, of the shape shown in Figs. 5 and 6 is positioned transversely of the machine in front of the front end of the measuring roller and back 20 of the plate 11 on which it is pivotally mounted between its ends at 21. One end of the member has a rearwardly extending arm 22 (Fig. 8) which extends parallel to the axes of the rollers 7 and 12 to one side of 25 their line of contact engagement. The opposite end of the member is extended beyond the pivot 21 for a distance as shown at 23 to lie under a lever 24 pivotally mounted between its ends at 25 to a side plate 11^a. The 30 opposite end of lever 24 (Figs. 2 and 5) extends to cam 17 which is provided with a second cam projection 17^b, shaped so that on rotation of the shaft 18 said end of the lever is elevated through movement of the cam, 35 the opposite end of the lever depressed, and member 20 turned on its pivot 21, thereby elevating the end of the member at which the arm 22 is located. The roller 12 is simultaneously lowered, as before described 40 and the slot at 5 is left clear for the placing of the cloth 6 between the rollers, as at the beginning of a measuring operation.

A roller carrying cage is loosely mounted on and around the housing 10. The cage 45 comprises two ring shaped ends 26 and 27 (Fig. 7) connected by pairs of bars 28 at opposite sides of the rings, the bars of each pair being spaced apart to provide a longitudinal recess 29 between them. The outer 50 end ring 27 has two spaced apart pins 30 projecting therefrom, and at the inner end ring a sheet metal circular member 31 is secured by screws (Fig. 1) to complete the cage and close the ends of the recesses 29, retaining the rollers 32 located in such recesses 55 from endwise movement. The cage is stopped from endwise movement on the housing by the head of screw 31^a which passes through the housing to hold the roller 60 bearing in place, the ends of pins 30 coming closely adjacent the supporting plate 11 to insure against outward endwise movement of the cage. It will be noted that in the normal position of the cage with the rollers 32 65 therein, the rollers tend to run down the in-

cline on the upper sides of the lower bars 28 until stopped by engaging against the flattened sides 10^a of the housing 10 as shown in Fig. 3.

A second irregularly shaped member of flat metal, shown at 33 (Fig. 5) is pivotally mounted between its ends at 34 on the plate 11, the downwardly extending end thereof below the pivot being forked, as at 35, to connect with a pin 36 projecting from the member 20. The member 33 extends horizontally and slightly upward in the other direction away from the pivot, is then turned in a downward direction substantially to the plane of the pins 30 and terminates in 80 an inturned end 37 which passes between the two pins. A spring 38 of slight strength is connected to the heavier end of the member 33 serving to substantially balance the same. (See Figs. 5 and 6).

With this construction, with the cloth 6 located under and elevating the bar 22, the irregularly shaped member 20 is turned about its pivot thereby giving a limited movement to the second irregularly shaped member 33, serving to hold the roller cage and rollers 32 therein in the position shown in Fig. 3, the measuring roller being freely rotatable. As soon as the end of the cloth passes by the measuring and presser rollers, the bar 22 drops to the position shown in Fig. 6, with an actuation of the member 33 and a turning of the roller cage and rollers to the position shown in Fig. 4, the rollers 32 being moved outwardly to engage against the inner sides of the measuring roller 7, such movement being caused by the travel of the rollers 32 on the flattened sides 10^a of the housing 10. A wedging action is provided serving as a sure brake against further movement of the measuring roller until the member 20 is turned in an opposite direction. This is done by operating the operating handle 19 in a downward direction to separate the presser roller from the measuring roller this, as earlier described, operating lever 24 and through it the member 20 so as to raise the bar 22 to an upper position, holding it there to permit the introduction of a succeeding length of cloth for measurement and freeing the measuring roller from the brake action to permit freedom of movement thereof. This freedom of movement continues as long as cloth is under the bar 22 or until the end of a remnant 115 is reached, the brake action coming into play immediately after the end of the cloth has passed from the measuring and presser rollers.

It is to be understood that there is shown only a portion of the machine or so much as is necessary to illustrate the invention. The complete machine is shown in my Patent No. 1,420,612, issued June 20, 1922. In machines of this character the cloth 6 is placed 120 125 130

between the rollers 7 and 12 when the same are separated by operating the lever 19, the member 20 being moved to elevate the part 22 thereof. When the lever 19 is moved back to original position, the member 20 is released and the part 22 thereof drops on to the upper side of the cloth, the roller 12 at the same time being elevated to press the cloth against the measuring roller which is operated by the frictional contact of the cloth therewith as it is drawn lengthwise between the rollers. When the end of a piece of cloth passes beyond the rollers, as illustrated in Fig. 6, the member 20 is released and acts to operate the member 33 and bring the brake into action to stop the roller 7 which cannot overrun and operate the measuring indicators further so as to indicate a greater measurement of cloth than has actually taken place.

Overrunning of the machine is positively prevented and an insurance made against charging the customer for more than is delivered. The construction is simple, durable and has worked perfectly in operation. The claims appended define the invention and all constructions coming within the scope thereof are to be considered as comprehended by said invention.

I claim:

1. In a machine of the class described, a measuring roller adapted to be driven by frictional contact of cloth therewith, brake means associated with said roller, and means for operating said brake means to operative or inoperative positions, said last mentioned means being moved to one position by cloth passing thereunder to operate said brake means to inoperative position and released on the passage of the cloth at its end therefrom for movement to another position to operate said brake means to operative position, substantially as described.

2. In a machine of the class described, a measuring roller adapted to be driven by frictional contact of cloth therewith, roller stopping means associated with the roller, and cloth controlled means for operating the roller stopping means to stop rotation of the roller on the passing of the end of a piece of cloth by the roller, substantially as described.

3. In a machine of the class described, measuring and presser-rollers between which cloth is adapted to be drawn to drive the measuring roller, means for moving said presser roller away from the measuring roller and holding it in such position, roller stopping means normally inoperative associated with the measuring roller, a member for operating said roller stopping means to operative position on dropping of one end of said member to a lower position, said end of the member being normally elevated by cloth passing between the rollers, and means

for elevating said end of the member on operation of the means for moving the presser roller away from the measuring roller.

4. In a machine of the class described, a measuring roller adapted to be driven by frictional contact of cloth therewith, brake means associated with said roller, a member connected with the brake means for moving it to either operative or inoperative position with respect to the roller, and a second member operatively associated with the first member to actuate the same, said second member being held in one position by the cloth when passing through the machine in which position the brake means is inoperative with respect to the roller, and moving to another position on passage of an end of the cloth by the roller, in which position the brake means is moved to operative position with respect to the roller.

5. In a machine of the class described, a shaft, a measuring roller secured thereto, a roller bearing for one end of the shaft, a cylindrical housing for the bearing having opposed flat sides, a cage loosely mounted on the housing, rollers carried in the cage between the flat sides of the housing and the inner sides of the measuring roller, and cloth controlled means connected with the cage for positioning it in inoperative and operative positions with respect to the measuring roller, turning the cage to wedge the rollers carried by the cage between the flat sides of the housing and the inner sides of the measuring roller when the end of a piece of cloth passes by the measuring roller, and turning the cage and rollers therein out of said wedging position to free the measuring roller for rotation when cloth is passing through the machine and driving the measuring roller.

6. In a machine of the class described, a shaft, a measuring roller secured thereto, a roller bearing for one end of the shaft, a cylindrical housing for the bearing having a flat side, a cage loosely mounted on the housing, a roller carried by the cage between the flat side of the housing and the inner side of the measuring roller, a member pivotally mounted between its ends and connected to the cage to turn the same a limited distance, a second member pivotally mounted and operatively connected to the first member for actuating the same, said second member being operated by cloth frictionally bearing against the measuring roller to move the cage to one position to permit free rotation of the measuring roller, and moving when freed of the cloth to move the cage to another position whereby the roller carried by the cage is wedged between the flat side of the housing and the inner side of the measuring roller to stop rotative movement thereof.

7. In a machine of the class described, a

- rotatably mounted measuring roller adapted to be driven by frictional contact of cloth therewith, roller stopping means located on the inner sides of the roller, and cloth controlled means for operating the roller stopping means into engagement with the roller on the passing of the end of a piece of cloth by the roller, substantially as described.
8. In a machine of the class described, a 5 rotatably mounted measuring roller adapted to be driven by frictional contact of cloth therewith, roller stopping means mounted to be moved into and out of engagement with the roller to stop the same or permit free rotation thereof, and cloth controlled means for operating the roller stopping means into engagement with the roller on the passing of the end of a piece of cloth by the roller, and out of engagement with said roller during 10 the time that cloth is operating the roller.
9. In a machine of the class, described a 15 rotatably mounted measuring roller adapted to be driven by frictional contact of cloth therewith, roller stopping means mounted to be moved into and out of engagement with the roller, cloth controlled means for operating the said roller stopping means into engagement with the measuring roller when the measuring and presser rollers are in operative engagement and an end 20 of a piece of cloth passes from between them, and means for simultaneously moving the presser roller away from the measuring roller and the cloth controlled means out of 25 the way for the entrance of cloth between said rollers, said movement of the cloth controlled means freeing the measuring roller for rotation.

for moving said cloth controlled means out 30 of the way for entrance of cloth into the machine, and leaving the roller free for rotation.

10. In a machine of the class described, a 35 rotatably mounted measuring roller, a presser roller for pressing cloth into engagement with the measuring roller, means for moving the presser roller away from the measuring roller for free entrance of cloth between the rollers, roller stopping means 40 mounted to be moved into engagement with the measuring roller, cloth controlled means for operating the said roller stopping means into engagement with the measuring roller when the measuring and presser rollers are in operative engagement and an end 45 of a piece of cloth passes from between them, and means for simultaneously moving the presser roller away from the measuring roller and the cloth controlled means out of 50 the way for the entrance of cloth between said rollers, said movement of the cloth controlled means freeing the measuring roller for rotation.

In testimony whereof I affix my signature.

ANTHONY VANDERVELD.
